UNITED STATES PATENT OFFICE.

ARRESTID DEMERS, OF SHERBROOKE, QUEBEC, CANADA.

BILLIARD-CUE, ROD, AND LIKE ARTICLE RACK HANGER AND LOCKER.

Application filed November 17, 1924, Serial No. 750,496, and in Canada December 24, 1923. Renewed May 11, 1927.

This invention relates to improvements in billiard cues, rods and like articles racks; and the objects of my invention are to hold said articles in suspension thereby preventing warping, etc., to develop in same, or if such defect already exists, to help correct same, affording at the same time a very convenient and efficient way to operate an individual locking of said articles.

10 These objects are attained by the mechanism illustrated in the accompanying drawings, in which—

Figures 1 and 2, show respectively the left side and front elevation of the rack hanger and locker, holding a cue and arranged for high positioning on the wall,

15 Figures 3 and 4, show front and right side elevation respectively, of the rack hanger and locker holding a cue and arranged for low positioning on the wall,

Figures 5, 6 and 7, show respectively top, elevation and bottom detail views of the rack hanger and locker, when opened,

20 Figures 8, 9 and 10 show respectively top, elevation and bottom detail views of the rack hanger and locker when closed,

Figure 11 shows in detail the left side elevation of the rack hanger and locker when closed.

25 Each piece of the apparatus bears a numeral of reference, and the same or similar pieces bear the same numeral in the different figures as well as in the specification.

The arrangement consists principally, referring to numerals:

1.—A bar jaw shaped and means for positioning same.

2.—A bar so offsetted at its ends as to form a jaw, pendant of 1, at the upper end, and at the lower end a part of a circle finished in a goose neck with a flattened portion to act as handle, part of centering ring as said ring acts on suspended article as to keep same centered in relation to upper jaws and locking device.

3.—A bar U shaped and means for positioning same.

4.—A spring attached to the movable jaw formed of bar 2, and otherwise stopped at the lower end.

5.—A bar partly shaped as to almost complete the circle formed at the lower end of bar 2, completed at its end by a slight outward curve, said end of the bar being split open as to allow to engage the gooseneck

part of bar 2, and means for positioning same.

6.—Sockets supporting bar 2, and means for positioning.

7.—Shelf, bracket or other support.

8.—Pads to allow of the retaining of the article placed for suspension without marking or otherwise marring same.

9.—Padlock which might be used to lock the apparatus.

10.—Article suspended in apparatus, represented here as a billiard cue.

By pressing on handle part of bar 2, said bar rotates in sockets 6, forcing the movable jaw and part of centering ring to open.

The tip end of article 10, is then placed against stationary jaw 1 and stopper 3, which prevents it from advancing too far,

the butt end of article being placed against stationary part of centering ring 5, the handle being then released. Through the action of spring 4, on the bar 2, the movable jaw and part of centering ring are forced to close, the jaws retaining the article suspended in the centering ring.

Being suspended, the weight of said article acts to keep it straight, or with the action of the centering ring, correct deviations. The shelf may be placed indifferently according to the position of the rack, so as to prevent the article being taken by forcing same up or down according to the position of the rack.

The length of the bar 2, between offsets may be varied to suit the positioning on the wall or background. By inserting a padlock in the ring formed between the outward portions of 2 and 5, the apparatus is securely locked.

What I claim as my invention and want to secure by Letters Patent:

1. A cue, rod or the like rack, comprising a rotatable rod having convenient offset portions forming a movable jaw and a working handle, a stationary jaw conveniently secured to a stationary object, bearing means for said rod, said stationary jaw co-operating with said movable jaw, said jaws having a spring so adapted as to normally keep them closed while allowing the placing of an object between them, which is then held in place.

2. A cue, rod or the like rack, comprising a rotatable rod having convenient offset portions forming a movable jaw and working handle, a stationary jaw conveniently secured to a stationary object, bearing means

for said rod, said stationary jaw cooperating with said movable jaw, said jaws having a spring so adapted as to normally keep them closed, while allowing the placing of an object between them, said object hanging suspended in place.

3. A cue, rod or like article rack, comprising a rotatable rod having convenient offset portions forming a movable jaw and working handle, a stationary jaw conveniently secured to a stationary object, bearing means for said rod, said stationary cooperating with said movable jaw, said jaws having a spring so adapted as to normally keep them closed and so shaped or equipped as to limit the insertion of the object while same is being placed or suspended.

4. A cue, rod or like article rack, comprising a rotatable rod having offset portions forming a movable jaw and working handle, a stationary jaw conveniently secured to a stationary object, bearing means for said rod, said stationary jaw cooperating with said movable jaw, said jaws having a spring so adapted as to normally keep them closed and so shaped or equipped as to limit the insertion of the object to be held, having a conveniently placed centering ring.

5. A cue, rod or like article rack, comprising a rotatable rod having offset portions at each end constituting movable jaws and handle, stationary jaws provided with means whereby they may be secured to a stationary object, and bearing means for said rod, upper stationary jaw cooperating with upper movable jaw and so made as to be able to receive and hold article adjacent its upper end, said jaws being so shaped or equipped as to limit the insertion of said article, lower stationary jaw and lower movable jaw co-

operating so as to form a centering ring for the suspended article, said jaws being normally kept closed through the action of a suitably placed spring.

6. A cue, rod or like article rack, comprising a rotatable rod having offset portions at each end constituting movable jaws, stationary jaws provided with means whereby they may be secured to a stationary object and bearing means for said rod, said stationary jaws cooperating with said movable jaws to receive the article adjacent the tip and butt ends respectively, a stop means adapted to limit the insertion into one of the pairs of jaws the other pair being so shaped as to act as centering ring and as to allow means to insert a padlock for locking purposes, other bearing means for said rod adapted to be secured to a stationary object, spring means adapted to normally keep the jaws in a closed position.

7. A cue, rod or like article rack, comprising a rotatable rod having offset portions at each end constituting movable jaws, stationary jaws cooperating with said movable jaws to receive the article adjacent the tip and butt ends respectively, stationary jaws provided with means whereby they may be secured to a stationary object, bearing means for said rod, a stop means adapted to limit the insertion into one of the pairs of jaws, the other pair being so shaped as to act as centering ring and as to allow to insert a padlock for locking the apparatus, other means for said rod adapted to be secured to a stationary object, spring means adapted to normally keep the jaws in a closed position, said apparatus adaptable for positioning on wall or other background.

ARRESTID DEMERS.
